CLAIM

The ornamental design for a top light panel, as shown and described.

DESCRIPTION

FIG. 1 is a front elevational view of a top light panel showing my new design, the panel being transparent so the appearance of the rear is substantially the same as the front thereof; and

FIG. 2 is an enlarged fragmentary cross-sectional view thereof taken along line 2-2 of FIG. 1.

FIG. 1

FIG. 2

UNITED STATES PATENT AND TRADEMARK OFFICE
CERTIFICATE OF CORRECTION
